The ornamental design for a synthetic cork for a liquid container, as shown and described.

DESCRIPTION

FIG. 1 is a front isometric view of a synthetic cork for a liquid container, such as a bottle of wine, showing my new design; the rear isometric view being substantially similar, the only difference being the random surface indicia thereon. FIG. 2 is a front side elevational view thereof; the rear side elevational view being substantially similar; and,

FIG. 3 is a top plan view thereof; the bottom plan view being identical thereto. The broken lines in FIGS. 1-3 are for illustrative purposes only and form no part of the claimed design.

The characteristic feature of my new design resides in the surface indicia of a marbled texture with a visible random curling effect.
